UNITED STATES PATENT OFFICE.

WALLACE PECK, OF BROOKLYN, NEW YORK.

BED FOR AUTOMOBILES, BOATS, ETC.

Application filed January 16, 1922. Serial No. 529,418.

To all whom it may concern:

Be it known that I, WALLACE PECK, a citizen of the United States, residing in the borough of Brooklyn, county of Kings, city 5 and State of New York, have invented certain new and useful Improvements in Beds for Automobiles, Boats, Etc., of which the following is a specification.

The object of the present invention is to 10 provide a commodious and comfortable bed for automobile and boat camping.

With this end in view the invention comprises a bed designed to be supported within the canopy hood or top of an automobile or 15 boat and suspended wholly through suitable means from the bow frames of said top. In carrying out this invention the improved bed has been designed on the collapsible plan so that when not in use it can 20 be rolled into a compact package and supported by suitable means in the curve of the top or hood at one side, thereby avoiding the use of storage room in the car or boat which could be otherwise used.

25 In order that the invention may be fully understood it will first be described with reference to the accompanying drawings and afterwards more particularly pointed out in the annexed claims.

30 In said drawings:—

Fig. 1 is a partial side elevation of a motor car of the Ford type, showing the canopy top or hood in section with the improved bed supported therein in position for use.

35 Fig. 2 is a plan view of the same.

Fig. 3 is a transverse sectional view taken on the line 3—3 of Fig. 1 and looking forwardly of the car.

40 Fig. 4 is a similar view with the bed collapsed and rolled up for storage in the curved part of the top or hood.

Fig. 5 is a detail sectional view showing one of the detachable fastening devices which are mounted upon the frame bows 45 for engaging straps that prevent lateral movement of the bed when in use.

Fig. 6 is a detail longitudinal sectional view showing parts of the canopy top frame and parts of the bed and its supports.

50 Fig. 7 is a detail view of one of the side bars of the collapsible bed.

Fig. 8 is a detail plan view of a portion of the bed showing the supports folded up ready for rolling up the bed.

55 Figs. 9, 10 and 11 are detail views of certain frame parts.

It should be understood at the outset that the present invention relates to improvements in a collapsible, camping bed designed to be mounted within the canopy top 60 or hood of an automobile, boat or other passenger vehicle, so that it can be conveniently stored within the canopy top when not in use and can be readily unpacked and secured in position for use when desired. In 65 the accompanying drawings the bed is illustrated as mounted within the canopy top or hood of a Ford type of automobile, but it must be understood that this is only illustrative of the principle involved and that 70 it is the intention to cover the invention in combination with any form of canopy top for passenger vehicle, boat, etc., of any type in which the principles of the improved bed are embodied.

75 1 is the body of any form of automobile, boat or other passenger conveyance. This body 1 is provided with a common form of canopy top or hood 10 in which 5 is the rear frame bow and 6 and 7 the intermediate frame bows mounted upon the vehicle body in any suitable way. 8 is the front bow mounted upon the forward bow 7 and usually connected to the dash or other part of the vehicle body by straps, braces or 80 other devices. The canopy top or cover 10 is stretched over the frame bows 5, 6, 7 and 8 and secured in place in the usual manner.

85 The specific form of bed for use within the canopy top, shown in the accompanying drawings, consists of a canvas or other strong web 15 with its side edges bound and formed with longitudinal pockets 16 to receive the side bars 17 presently to be referred to. This web of flexible material 15 is engaged along its central longitudinal line by upper and lower plates or bars 20—21, which can be shifted longitudinally upon each other to obtain the desired length and are securely fastened together with the bed 90 webbing 15 confined between them by means of a series of screws 22.

95 Each of the plates or bars 20—21 is formed with a reduced threaded end 20^a or 21^a to receive a block 25 and a plate 26, 105 which are confined in place by a nut 27 screwed upon threaded end 20^a or 21^a or some other suitable means. The block 25 is formed with oppositely presented spaced ears 25^a, between each pair of which is pivotally mounted a reduced end of a spreading end plate or bar 30, which is formed at its 110

outer end with a curved recessed blade 31 designed to engage an annular groove 17^a formed in the heads attached to the opposite ends of side bars 17 above referred to.

5 It will be observed that a pair of spreading and bracing arms 30 upon block 25 is provided at each end of the bed, so that when all four arms 30 are in proper position in engagement with the ends of side bars 17, the bed will be stretched and supported in open position as shown in Figs. 1, 10 2 and 3 of the drawings. The bed shown is designed to accommodate two persons.

In changing the length of the bed by 15 means of the adjustable longitudinal bars 20-21 referred to, it will be understood that it will be necessary to provide the proper length of bed webbing 15 and side bars 17 to suit the length of the bed desired. These 20 dimensions are, of course, arranged before attempting to mount the improved bed in a particular boat or car, and after the dimensions have been properly determined there is never any occasion for changing the 25 same in a particular installation. The central longitudinal bars 20-21 are shown in two parts for adjustment, but a single rigid bar of any desired shape may be used if preferred.

30 As stated above a plate 26 is properly pivoted upon a reduced end of each of the bars 20-21. Each of these plates 26 is adjustably connected with a plate 35 by means of pins or bolts 36, which pass through openings in said plates. One of each pair of 35 plates 26-35 is provided with a series of openings, such as indicated at 37, whereby the supports formed by said plates may be adjusted in length.

40 Each plate 35 carries at its upper end a flanged head 40 adapted to rest in a socket 41 secured to one of the frame bows as will presently be more clearly explained. A thumb screw 42 is threaded through each 45 plate 35 and head 40 to engage the inner wall of the supported socket member to hold the bars tightly in place and prevent rattling.

Each of the members 30 has pivotally attached to it at 45 a brace rod 46 formed with 50 a plurality of hooks such as indicated at 47 to engage a screw or stud such as 48 mounted in one of the plates 35. The screws or studs 48 can be mounted in different locations on the plate 35 to suit adjustments in 55 the length of the supports 26-35. For instance, as shown particularly in Fig. 3, the screw 48 can be moved to the lower hole 49 of plate 35, thereby supporting the bed at 60 a higher level in the hood and in which position the stays 46 will be held by the engagement of their lower hooks 47 with the studs 48.

65 It will be understood that the braced supports for the front and rear ends of the im-

proved bed are designed to suspend the bed centrally in the body of the car, boat or other vehicle, and that the vertical adjustment of the supports is provided so as to suspend the bed at the proper elevation to just clear the backs of the seats in the car or other vehicle. It sometimes happens that the distance between the supporting front and rear frames of the top or hood and the seat backs of the vehicle is less than half the width of the top or hood, so that in using the bed suspending supports upon which to move the collapsed bed into stored position under the hood, it becomes necessary to provide means for compensating for this difference as otherwise the collapsed bed would not be presented in the desired location in the top curve at one side.

To arrange for this difficulty, I provide 80 double sockets 41-61 on each end of the top, the sockets 61 being located the same distance from the curved side of the top as the sockets 41 stand above the seat backs; so that when the bed is collapsed and rolled up the flanged heads 40 are slipped out of 85 sockets 41 and into sockets 61 and rotated upon said sockets 61 until the rolled up bed is presented in the side curve of the top, where it may be fastened with any suitable means such as by a tape or strap as indicated in Fig. 4 of the drawings.

When the bed is supported in position for use, it is held against lateral swaying by any suitable means such as for instance as the perforated straps 70, suitably attached to 100 the sides of the bed and designed to be engaged with hooks 75 detachably mounted upon the intermediate side bows 6 and 7, so as to be moved into and out of operative 105 position as indicated in dotted lines in Fig. 4. It will be understood that any suitable means may be employed for securing the bed against lateral movement upon its suspending supports.

The sockets 41-61 at the front of the car 110 top are suitably mounted upon a transverse brace or bar 80, provided at its ends with suitable clamping devices 81 as shown in Fig. 9 of the drawings to adjustably support it upon the forward bow 8 of the top 115 frame. At the rear of the top the sockets 41-61 are shown in the form of a metal casting suitably secured to the top of the rear bow 5 of the top frame.

When it is desired to store away the bed, 120 the braces 46 are disengaged from studs 48 and the braces 30 are disengaged from the heads of side bars 17. Braces 30 with stays 46 are then folded inwardly into position shown in Fig. 8 of the drawings, and leaving the side bars 17 in their side pockets, the bed is rolled up by rotating the central supporting bars 20-21 in the supporting plates 26. When properly rolled up the flanged heads 40 are transferred from sockets 41 to 130

61 and the rolled up bed sways upon these supports into the position shown in Fig. 4. Anti-rattler thumb screws 42 are then tightened up to hold the parts in position.

5 In cases where the bed is applied to a canopy top which is sufficiently high to provide a drop of one half its width for the bed supports, it will be understood that then it will be necessary only to provide a single socket 16 41 on each end of the canopy frame for supporting the bed both in stored position and lowered position.

I claim:—

1. The combination of a collapsible bed 15 adapted to be supported above the seats in a covered vehicle, with supports pivotally connected with said bed, and mounting means pivotally engaging said supports, said mounting means being constructed for 20 attachment to a vehicle top, whereby said bed can be suspended from the vehicle top in open position or be collapsed and rolled into compact form upon said supports and moved into storage position beneath the vehicle top.

25 2. The combination of a bed for covered vehicles, with braced supports connected with said bed at its opposite ends within the vertical central longitudinal plane of the bed, said supports having means for attachment 30 to the vehicle top at a plurality of points.

3. In a bed adapted to be supported by the top of a passenger vehicle, the combination 35 of suspension supporting members constructed for suspension from a vehicle top, and mounting members pivotally engaging said supporting members and constructed for attachment to a vehicle top, with a collapsible bed rotatably mounted upon said 40 suspension supporting members.

4. In a bed adapted to be supported by the top of a passenger vehicle, the combination 45 of mounting members adapted to be attached to a vehicle top, and suspension supports pivoted upon said mounting members, with a collapsible bed rotatably mounted upon said suspension supports, and braces 50 detachably connecting said bed and supports to hold the bed in open position for use.

5. In a bed adapted to be supported by the top of a passenger vehicle, the combination 55 of mounting members adapted to be attached to a vehicle top, and suspension supports pivoted upon said mounting members, with a collapsible bed rotatably mounted upon said suspension supports, braces 60 detachably connecting said bed and supports to hold the bed in open position for use, and fastening devices for securing the braced bed and supports against lateral movement in the vehicle top.

6. In a bed adapted to be supported by the top of a passenger vehicle, the combination 65 of mounting members adapted to be attached to a vehicle top, and suspension sup-

ports pivoted upon said mounting members, with a collapsible bed mounted upon said supports and comprising longitudinal bars, end members engaging said longitudinal bars and holding them in spread apart relation, and a bed webbing supported by said bars.

7. In a bed adapted to be supported by the top of a passenger vehicle, the combination 70 of mounting members adapted to be attached to a vehicle top, and suspension supports pivoted upon said mounting members, with a collapsible double bed rotatably mounted upon said suspension supports within the vertical central longitudinal 75 plane of the bed.

8. In a bed adapted to be supported by the top of a passenger vehicle, the combination 80 of mounting members adapted to be attached to a vehicle top, and suspension supports pivoted upon said mounting members, with a collapsible double bed rotatably mounted upon said suspension supports within the vertical central longitudinal 85 plane of the bed, and braces detachably connecting said bed and supports to hold the bed in position for use.

9. In a bed adapted to be supported by the top of a passenger vehicle, the combination 90 of mounting members adapted to be attached to a vehicle top, and suspension supports pivoted upon said mounting members, with a collapsible bed mounted upon said 95 suspension supports, and means for securing the collapsed bed in stored position beneath the vehicle top.

10. In a bed adapted to be supported by the top of a passenger vehicle, the combination 100 of mounting members adapted to be attached to a vehicle top, and suspension supports pivoted upon said mounting members, with a collapsible bed rotatably mounted upon said suspension supports, braces 105 detachably connecting said bed and supports, and means for securing the rolled up bed in stored position beneath the vehicle top.

11. In a bed adapted to be supported by the top of a passenger vehicle, the combination 110 of mounting members adapted to be attached to a vehicle top, and suspension supports pivoted upon said mounting members, with a collapsible bed mounted upon said 115 supporting members;—said collapsible bed comprising a web, a plurality of longitudinal bars supporting said web, and folding end frames engaging and spreading said longitudinal bars and detachably engaging the ends of said side bars, said end frames being adapted to be disengaged from active position and folded inwardly against the central longitudinal bar, whereby the collapsed end frames and longitudinal bars can be rolled up within the bed webbing upon said supporting members.

12. In a bed adapted to be supported by 130

the top of a passenger vehicle, the combination of mounting members adapted to be attached to a vehicle top, and suspension supports pivoted upon said mounting members, 5 with a collapsible bed mounted upon said supporting members;—said collapsible bed comprising a web, a central longitudinal bar and two side bars supporting said web, folding end frames mounted upon said central 10 longitudinal bar and detachably engaging the ends of said side bars, braces mounted

upon said end frames and detachably engaging said supports;—said end frames and braces being adapted to be disengaged from active position and folded inwardly against the central longitudinal bar, whereby the end frames, braces and side bars can be rolled up within the bed webbing by rotating the collapsed bed upon its central longitudinal bar. 15

WALLACE PECK.
